CROWN-BRANDING ATTACHMENT FOR BOTTLING-MACHINES.

No. 909,396.

Specification of Letters Patent.

Patented Jan. 12, 1909.

Application filed January 21, 1908. Serial No. 411,979.

To all whom it may concern:

Be it known that we, FRED M. GILMORE, and MARTIN H. MULKEY, citizens of the United States, and residents of the city of Seattle, in the county of King and State of Washington, have invented a new and useful Improvement in Crown-Branding Attachments for Bottling-Machines, of which the following is a specification.

10 Our invention relates to improvements in crown branding and bottling machines, whereby the crowns may be branded automatically by, and during the operation of the bottling machines, without necessity of special 15 attendance for this purpose.

Our invention comprises the combinations of parts defined by the claims terminating this specification.

The object of our invention is to simplify 20 and improve the mechanism and methods used in branding bottle crowns and particularly to enable this work to be done in connection with the crowning of the bottles and automatically by an attachment which 25 is operated by or in connection with the crowning machine.

The drawings accompanying this specification show our invention embodied in the form which is now preferred by us.

30 Figure 1 is a side elevation with parts in section, of parts of a crowning machine having our branding attachment mounted thereon. Fig. 2, is an end elevation of our attachment, the frame thereof being in section.

35 Fig. 3 is a side view of the same with the side plate of the frame removed, the parts being in the working position. Fig. 4, is a sectional view of the branding head and the means which may be employed for heating it when

40 gas or gasoline is employed for this purpose. Fig. 5, is a transverse section through one of the tappet pins and its nut, employed for actuating the branding attachment. Fig. 6 is a separate view of the spring employed for

45 holding these tappet pins as placed. Fig. 7 is a view of the complete crowning machine showing the manner of mounting and connecting our device thereto.

In connection with the bottling of liquors 50 where metal caps or crowns are used having a cork washer between the crown and bottle end, it is a common practice to brand the inner surface of the cork washer, as by placing thereon figures indicating the date when it

55 was bottled, or any other matter which it may be considered desirable to have thereon.

As commonly done, this involves two distinct operations conducted upon two distinct machines and requiring separate attendants. By our invention we provide an attachment which may be connected with the crowning machine and operated automatically thereby, whereby the crowns may be branded in connection with the operation of the crowning machine and as needed, thereby avoiding much of the expense of the ordinary branding machines and the entire cost of attention for such branding machines.

In Fig. 7 is shown a crowning machine of a type, for attachment to which, our invention is peculiarly adapted. This machine has a hopper A, for the reception of the crowns, a feeding device B, by which the crowns are selected and properly disposed for delivery to the feed chute C, by which they are delivered to the revolving disk, D, carrying a plurality of crowning heads E. The bottles to be crowned are placed upon a revolving table beneath the disk D and when they reach the point occupied by the bottle F', the bottle is forced upwards into the crowning head, where the crown is secured thereon. These parts are such as are in common use in machines now on the market, and, except as they are combined with features characteristic of our invention, are not claimed by us. These parts are illustrated and herein mentioned simply to show a type of machine with which our invention may be used, and the manner of applying it thereto. This mechanism being old and common, will not be herein described, except as may be necessary to illustrate the connection and operation of our invention.

The chute C, through which the crowns are delivered from the hopper to the base of the crowning heads E, has an opening extending throughout its length, of such a size and shape as will accommodate the crowns singly, that is, without superposition. Usually this chute has a central longitudinal opening or slot in its outer face which permits visual inspection to determine whether the crowns are being properly fed. For our purpose, an opening in the face of this chute should be provided of sufficient size that the crowns may be branded while passing through the chute. The slot spoken of may, in many cases, be sufficient for this purpose.

Our device, represented in its entirety by the character G, is attached to this chute, as is shown in Figs. 1 and 7. This device has a

- branding head 12, which is secured to one end of a cylinder 1. This cylinder is mounted to reciprocate lengthwise and in line with the opening in the feed chute C, of the crowning machine. The cylinder 1 is supported by two plates, 10 and 11, which are in turn supported by sleeves or tubes, 2, sliding upon rods 20, which connect the outer face 54 of the frame with the inner face 5. 5
- 10 The branding head 12, may be heated in any suitable or convenient manner. The manner contemplated in the device as shown in Fig. 1 is by means of an electric heating coil which is supplied with current through the conductors 93. This branding head may, however, be heated by means of gas or gasolene, which is contemplated in the device as shown in Fig. 4. In this latter, a tube 9, which carries the mixture of combustible and air, is mounted in the center of a cylinder 1, with its inner end just back of the inner end of the branding head 12. This tube is provided with a small entrance for the gas, as shown at 90, and is adapted to receive the end of a supply tube 91. Air for mixture with the gas is admitted through the holes 93. The products of combustion escape from the cylinder 1 through the openings 13. 15
- 20 25 30 35 40 45 50 55 60 65 70 75 80 85 90 95 100 105 110 115 120 125 130
- The branding head and the cylinder 1 are held away from the chute C, and the crown therein, by means of two springs 28, which lie between the head 5 and the plate 11. These will compress and permit the advance of the branding head upon the crowns or to the position shown in Fig. 3. This advancement of the branding head is produced through the action of the shaft 3 and the forked arms 30, secured to this shaft which engage washers 21 secured upon the sleeves 2. This shaft 3 is actuated through a crank arm 32, link 33, and cam rod 40, which carries upon its end the cam 4, so placed as to be engaged by tappet members carried by the crowning heads. The connection between the arms 30 and the branding head is of a yielding character so as to compensate for possible differences which may occur in the thickness of the crowns or otherwise. 45
- The crowns which are placed loosely in the hopper A, are selected and properly disposed so as to be delivered one at a time and properly faced to the upper end of the feed chute C. These crowns slide down the chute C, but are checked by stop pins carried by our device so as to present them one at a time in proper position for being branded. These pins enter the chute towards its edge in the angles between the circles of the crowns. 55
- Two stop pins are provided, one pin 7, entering the chute in position to hold the crown which is being branded. The other pin, 70, is placed a sufficient distance lower down to engage and hold the crown which lies next 60 below the one which is being branded; and so

as to check downward movement of the row of crowns, so that the crown next above it will thereby be held in branding position during the time when the first pin 7 is withdrawn. These pins, 7 and 70, are connected to move alike and oppositely by means of a lever 6, which is connected to each of said pins and is pivoted upon a portion of the frame as for instance, the bar 52. The spring 61, is made of sufficient strength to be capable of overcoming the opposed spring 60, and hold the pin 7, advanced within the slot of the feed chute. This spring is so placed as to act between the lever 6, and one of the moving plates, 10 or 11. In Fig. 1, we have shown this spring as acting in tension between the plate 11, and lever 6; in Fig. 3 we have shown this spring as acting in compression between the plate 10 and lever 6. A spring 60 is provided, which acts between the lever 6 and a portion of the frame so as to insure the advancement of the stop pin 70, and the withdrawal of the pin 7, whenever the branding head is withdrawn to its normal position. The springs 60 and 61 act in opposite directions upon the same members, but the spring 61 is intended to be of sufficient strength to be able to overcome the action of the spring 60 when the branding head is advanced, and at other times to have a sufficiently slight initial tension as to not interfere with the action of the spring 60. 90

In the operation of a device of this character, it is desirable to have some means for indicating the fact in case the supply of crowns to the branding device should become interrupted. We have, therefore, provided an electric signaling device which will cause a bell to ring in case the branding device is operated without there being a crown in position for branding. This device as shown is as follows: An electric signal bell 83, of any suitable construction, is provided, together with a battery 82 or other source of electricity. One side of the circuit 81, is connected with a metal plug 8, which is mounted within an insulating washer 80, so as to be in direct line with the branding head. The other side is connected in any suitable way with the branding head. The crowns which are being branded have a cork, or like washer, on their inner surface, upon which the branding head acts. When, therefore, the branding head meets one of these crowns, electric connection will not be made between the two branches of the signaling circuit, and the bell will not ring. When, however, a crown is missing, the crowning head will advance until it contacts with the plug 8, thus completing the circuit and causing the bell to ring. 110

The type of machine upon which we have shown our device as mounted, has a revolving disk or table D, upon which are mounted a series of crowning heads E. Beneath the disk D is a rotating table carrying supports 115

for the bottles F. As these tables revolve, the mechanism causes the bottles to rise up when they reach the point F'. This bottle is forced upward powerfully against the crowning head, and by such action the crown is secured upon the bottle. This type of machine carries within each crowning head a reciprocating member or plunger, the upper end of which is shown at 46 in Fig. 1. This reciprocating member is held downward by a powerful spring 48, which spring furnishes the resistance against which the crowning is done. The crowning heads E, or the casing which contains the crowning mechanism, are inclosed at the upper ends by means of caps 49.

The members so far described are those which are common in machines of this type. We have made one slight change in the construction in order to adapt the machine to the operation of our device.

In the upper end of the reciprocating member 46, we have drilled an axial hole 47, within which reciprocates one end of the tappet pin 43. In the upper portion of the cap 49 we have made a hole which receives one end of the plug 44, which is threaded and secured in place by means of a nut. This plug 44, contains a hole of such size as to receive the pin 43, and permit its end to be projected above the same, or into the position shown in Fig. 1. This pin is of such length that it may be forced downward to such an extent that its upper end is flush with the upper end of plug 44. The cam 4, by which the crown-brander is operated, is so placed that it will be engaged by these tappet pins 43, as they are carried about by the revolution of the table D. If these pins are projected when they reach cam 4, they will force the cam backward, thus reciprocating rod 40, and through the mechanism described actuating the branding head. If, however, one of these pins is not projected, the cam 4, will not be moved when the corresponding crowning head passes the same. By this principle we secure the operation of the branding head in correspondence with the actual crowning operations performed. In other words, if the crowning of a bottle is omitted, the brander will not operate when this crowning head reaches it.

We provide means of a yielding character, and of sufficient strength to hold the tappet pins 43, in whatever position they may be placed, until they are acted upon by some stronger force. Such means as shown consists of providing the pin with peripheral grooves, and engaging these grooves by a spring catch. The spring catch illustrated is shown separately in Fig. 6, and in connection with the plug in Figs. 1 and 5. The spring consists of a wire 46^a, and is bent in the form of a ring and lies within a groove 65 formed about the plug 44. One end of this

spring is bent inwardly, as shown in Fig. 6, and passes through a radial hole in the plug, and engages with the grooved surface of the pin 43, to hold it in whatever position it may be placed. These pins are elevated by the action of placing the crown upon the bottle, and remain elevated until they have passed the cam of the branding attachment. After passing this attachment they are engaged by a spring 71, which is mounted on the lower surface of the hopper A, and within a recess 72 of such character that in case one of the pins should become stuck and refuse to depress, the spring may be forced upward into this cavity and there would be no breakage of parts. This spring is of sufficient strength that it will depress all of the tappet pins as they pass beneath it. If, therefore, a crowning head is not actuated or loses its crown when passing the crowning position, its corresponding pin 43, will not be projected, and when this crowning head reaches the cam of the branding attachment, it will not actuate the same.

We have herein shown and described the mechanisms which we have preferred to adopt in applying our invention to one type of crowning machines.

We are aware that the principles of our invention might be otherwise embodied as applied to machines of other types, and that the construction of the members may be varied from those shown as applied to machines of this particular type. We do not, therefore, wish to be limited to the exact mechanisms herein shown and described, but claim our invention broadly as expressed in the claims.

What we claim is,

1. The combination with a bottle crowning machine, of a crown-branding device, means for normally holding the branding member thereof out of engagement with the crown, and means for operating the crown-branding device by the crowning machine to brand the crowns only as fed to the crowning machine.

2. The combination with a bottle-crowning machine, of a crown-branding attachment, means for operating said attachment from the crowning machine, and means for preventing the branding action of said attachment except as the crowns are fed.

3. A crown-branding attachment adapted for attachment to and operation by a bottle crowning machine, and normally held in inoperative position, and means for operating said attachment from the bottle crowning machine.

4. A crown-branding attachment for bottle crowning machines normally held out of branding position and means for operating said attachment from the crowning machine controlled by the prior crowning action of the crowning heads.

5. A crown-branding device adapted for attachment to a bottle crowning machine, means for operating said device from the crowning machine, and means for preventing 5 more than one application of the branding member to the crown.
6. A crown-branding attachment for crowning machines, actuating cam pins for said attachment carried by the crowning 10 heads, and means controlling the action of said pins by the prior crowning action of said crowning heads.
7. A branding attachment for bottle crowning machines adapted to be operated 15 through the movement of the crowning heads, special actuating means for said attachment carried by each crowning head, and means controlling the operativeness of said actuating means for each head by the 20 act of applying a crown by said head.
8. The combination with a bottle crowning device, a crown-feeding device, and a crown-branding device acting upon the crowns in their passage through the feeding 25 device, of means for actuating the crown branding device controlled by the prior placing of a crown upon a bottle.
9. The combination with a bottle crowning machine and a crown-branding device, of 30 a member for actuating the branding device, and means for rendering said member operative through the action of a bottle when it is crowned.
10. The combination with a bottle crowning machine having a plurality of crowning heads, and a crown branding device, of 35 means carried by each crowning head and movable relative thereto for actuating the branding device, means normally placing 40 said brander-actuating means in non-operative position, and means actuated by the bottles when crowned for placing said brander actuating means in operative position.
11. A crown-branding device comprising 45 a chute for the single-file passage of the crowns, a branding head movable to engage the crowns in said chute, two stop pins connected to move with said head and to be alternately inserted in said chute above and 50 below the crowns as branded.
12. A crown-branding attachment for bot-

tle crowning machines, comprising a movable branding head, a crown chute, stops actuated by said branding head controlling the feeding of the crowns, a cam for actuating said branding head, and a movable tappet member carried by each crowning head and moved into position to engage said cam by the operation of crowning a bottle.

13. In a bottle crowning machine, in combination, a plurality of crowning heads each having a crowning member reciprocated by the bottle during crowning, tappet members each moved by the reciprocation of its particular crowning member, and means for holding said tappet members as so moved until acted upon by a superior force, and a crown branding attachment positioned to be actuated by said tappet members when projected.

14. In a bottle crowning machine the combination with a crowning member reciprocated by the bottle during crowning, a tappet member reciprocated by said crowning member, means for yieldingly holding said tappet member as placed, a crown-branding attachment actuated by said tappet member and means for moving said tappet member from its operative position between the time of actuating the branding attachment and 70 crowning a bottle.

15. The combination with a bottle crowning machine having a plurality of crowning heads movable in an orbit and each having a crowning member movable by the bottle at 85 a point in said orbit, a crown-branding attachment and means for operating said attachment comprising a member movable into operative position by said crowning member, means for yieldingly holding said member as placed, and means for moving said member into inoperative position after 90 it has actuated the branding attachment.

In testimony whereof we have hereunto affixed our signatures, at Seattle, Washington, this 16th day of January, 1908.
